UNITED STATES PATENT OFFICE.

JOHN P. WEIS, OF NYACK, NEW YORK.

FEEDING MECHANISM FOR SEWING-MACHINES.

1,055,584.

Specification of Letters Patent.

Patented Mar. 11, 1913.

Application filed November 5, 1909. Serial No. 526,401.

To all whom it may concern:

Be it known that I, JOHN P. WEIS, a citizen of the United States, residing in Nyack, county of Rockland, and State of New York, have invented a new and useful Improvement in Feeding Mechanism for Sewing-Machines, of which the following is a description.

This invention relates to feeding mechanism for sewing machines and particularly to a type of mechanism applicable to stocking welting machines such as made the subject of my application filed October 11th, 1909, Serial No. 522,158.

Among the objects of my invention may be noted the following: to provide a simple, cheap, high-speed and easy-running feeding-mechanism particularly applicable to machines wherein the work is fed over and supported by either a horn or small flat work-support; to provide feeding-mechanism capable of being used in a machine having a restricted work-support and capable of sewing tubular articles of various kinds; to provide a feeding-mechanism embodying a construction wherein all the movements are positive and wherein the timing can be varied and made certain; to provide a feeding-mechanism wherein the feed-bar is supported and driven so as to reduce the possibility of rattling and objectionable vibration to a minimum; and to provide a construction whereby the feed-dog can be so adjusted relatively to the work-plate as to produce either an ordinary four-motion feed or a feed of the four-motion type and tilting variety.

With the above objects in view and others which will be detailed during the course of this description, my invention consists in the parts, features, elements and combinations of elements as hereinafter described and claimed.

In order that my invention may be clearly understood I have provided drawings wherein:

Figure 1 is an end view of so much of a stocking welting machine, such as is made the subject of my aforesaid application, as is deemed necessary to illustrate my invention, the view being an end elevation showing the feeding-mechanism with parts broken away and other parts in section; Fig. 2 is a view similar to Fig. 1, but illustrating the feeding-mechanism from the opposite side; Fig. 3 is a top plan view of Fig.

2 with certain parts broken away and showing in addition the horn and throat-plate or work-support of the machine; Fig. 4 is a rear elevation of Fig. 2; and Fig. 5 is a perspective view of the feed-bar and its lifting eccentric.

Referring to the drawings the numeral 1 indicates the bed-plate of the machine, 2 the looper-supporting plate, 3 the spreader-supporting plate, the two said plates being secured in any suitable manner and arranged at an acute-angle to each other. A journal-bearing 4 is secured to the plate 3 by means of one or more screws 5, the driving shaft 6 being journaled at one end in said bearing. The work-plate 7 has the depending end-web 8 secured to the bed-plate by means of one or more screws 9 and is supported on the post 10 extending upwardly from the bed-plate 1, a screw 11 making the connection between the two. The work-plate at its forward end supports the throat-plate 13 which extends beyond the depending web 8 as clearly shown in Figs. 3 and 4, said throat-plate being sustained in position by means of the extension 14 of said web 8 and also by the laterally projecting horn 15 which is arranged at the front end of said throat-plate 13, the latter being secured to said extension and horn by means of screws 16. The throat-plate is provided with slots 17 through which the feed-dog 18 operates, the latter being secured adjustably to its bar 19 by means of its grooved shank 20 which embraces the forward end of said bar and to which it is secured by means of the screw 21 extending through an elongated aperture or slot 22 whereby said dog can be raised or lowered on said bar relatively to the throat-plate through which it works. The feed-bar 19 has adjustably secured to it the angular arm or wire 23 the adjustment being secured by the vertical portion of said arm extending into the socket 24 where it is held by the screw 25 passing through the enlarged forward end 19a of said feed-bar and engaging the said arm. The bottom edge of said enlarged end of the feed-bar is given a V form as indicated at 23a, said edge being received in the groove 24 of the feed-lifting eccentric 25 fixed to the driving shaft 6, the form of the eccentric being illustrated in Figs. 1 and 5 by dotted lines and indicated by 26. The horizontal portion of the angular arm or wire 23 is also received in the groove 24 of the eccentric 25 and is arranged

on the side of said eccentric opposite the edge 23^a of the feed-bar 19. Thus the feed-bar is given its rise and fall and is supported steadily and without possibility of lateral movement or vibration, the rising and falling motions being both positive and easy. It will be noticed by viewing Figs. 3 and 5 that the feed-dog 18 is laterally offset from its shank and from the feed-bar as well as being extended forwardly into its operative position, the feed-dog being also arched on its bottom, as indicated at 27, for the purpose of permitting the looper 28 to operate close to the throat-plate, as clearly shown in Fig. 1. At its rear end the feed-bar is pivotally supported at 29 on the upper end of the curved driving-lever 30 which at its lower end is pivotally supported at 31 upon the bearing 32 by means of the journal-pin 20 or screw 33 passing through said bearing and into said lever 30. The journal 32 is part of the supporting-bracket 34 secured adjustably to the bed-plate 1 by means of screws 35, the adjustment being vertical and 25 secured by passing the said screws 35 through elongated slots 36 in said bracket 34. By this means the bracket can be set in the desired position to secure the proper location of the feed-dog relatively to the 30 work-support or throat-plate and also to enable the said feed-dog to be tilted if desired. Sliding upon the driving-lever 30 is the block 37 which embraces said lever and is prevented from falling away therefrom by 35 means of the cross-plate 38 either riveted or screwed thereto as indicated at 39. The block 37 has extending laterally therefrom the driving journal-pin 40 upon which is journaled the rear end of the driving-strap 41 the forward end of which encircles an eccentric 42 fixed to the driving-shaft 6, the 40 operations of which will transmit longitudinal reciprocations to said strap 41 and vibratory movements to said lever 30 and, through 45 the latter, longitudinal reciprocations to the feed-bar 19. The position of the sliding-block 37 is held by means of the adjusting screw 43 passing through the rear portion of said block and engaging the driving lever 50 30. By releasing the screw from its engagement with said lever, the block can be readily raised and lowered and the screw reset.

The throat-plate carries a guiding device for the edge of the work generally indicated 55 by 44 and portions of a trimming mechanism also carried by the machine are indicated by the numeral 45, these parts being all common to the stocking welting machine illustrated in my aforesaid application.

60 The looper 28 is supported by the carrier 46 journaled at its lower end upon the pin 47 operating in the bearings 48 of the looper-supporting plate 2; and the spreader 49 is carried by the spreader-carrier 50 journaled 65 upon the inclined plate 3. A trimmer-lever

45 is journaled in bearings of the work-supporting plate 7, and the stationary or ledger-blade thereof is shown at 51 the same being carried by a horn 15 forming part of the work-support in combination with the 70, throat-plate. These parts are not shown herein in detail but are illustrated only partially for the purpose of enabling their juxtaposition to be seen and determined relatively to the feeding-mechanism and the 75 stitching position. These several parts are shown and described in detail in my application for stocking welting machines Serial No. 522,158 filed October 11, 1909.

From the foregoing the mode of operation of my feeding mechanism will be clearly understood with the following additional brief description: The work intended to be operated upon by the stitching mechanism of the machine will be placed at rest upon the throat-plate and can be easily manipulated by the left-hand of the operator so as to hold the same up to its proper working position with its edge or edges against the guide 44. The rotation of the driving 80 shaft will cause the eccentric 25 to lift the feed-bar so that its dog will project through the throat-plate 13 whereupon the eccentric 42 will impart movement to the strap, which will in turn rock the driving lever 30, which 85 in turn will give longitudinal reciprocations to the feed-bar 19, the depression of the feed-bar and its dog being produced by the eccentric 25 operating upon the angular-bar 23. The eccentric 42 and the eccentric 25 90 are so timed relatively as to cause the feed-dog to rise into engagement with the work feed the latter rearwardly across the throat-plate, then be depressed from engagement with the work, and then moved forwardly 95 100 again into position to rise again into engagement with the work, this being the action of the ordinary four-motion feed-dog. The amount of feed movement or length of feed is regulated by adjustment of the block 105 37 upon the lever 30. The amount of the grip of the dog upon the work, or the pressure it will exert on the latter, can be regulated by the adjustment of the said dog vertically on its bar. The horizontal working 110 position of the feed-bar can be obtained quickly by the adjustment of the bracket 34 which supports the driving-lever on the bed-plate of the machine; and in addition to such adjustment the feed-bar and its dog 115 can be tilted relatively to the throat-plate by a further adjustment of said bracket 34 either upwardly or downwardly accordingly as it is desired to bring more or less of the length of the feed-dog into engagement with the work during the feed movement. That 120 is to say, if the bracket 34 be raised vertically to different degrees, the dog can be made to present more or less of its serrated surface from its rear end toward its front 125

end through the throat-plate for engagement with the work, or by adjusting the bracket 34 downwardly more or less, the forward end of the feed-dog will be raised 5 more than the rear end so as to cause said dog to present more or less of its serrated surface from front to rear through said throat-plate for engagement with the work. In other words, according to the adjustment of the bracket 34, the feed-dog can be given more or less of an inclination from front to rear or from rear to front, or can be caused to operate in planes parallel with the surface of the throat-plate.

10 15 From the foregoing it will be seen that the feed-mechanism is very strong and rigid, has little or no vibration, is positive in action, and is exceedingly simple.

Having thus described my invention what 20 I claim and desire to secure by Letters Patent is:

25 30 1. A feeding mechanism for sewing machines comprising a flat, narrow feed-bar; a feed-dog fixed to said bar and offset vertically and laterally from said bar and extending beyond the forward end of the latter; a flat, narrow, curved segment adjustably supported at one end and at its other end pivotally connected to the feed-bar; a connection adjustably secured to the segment for operating said feed-bar; and means for actuating said bar.

35 2. A feeding mechanism for sewing machines comprising a flat, narrow, feed-bar provided with a V-shaped bottom edge, a feed-dog carried by said bar; actuating means for said bar including a feed-lifting eccentric having a V-shaped groove in its periphery for coöperation with the bottom

edge of the feed-bar; a segmental arm pivotally connected to one end of said bar; means for pivotally supporting said segmental arm; a driving eccentric; and an adjustable connection between said eccentric and said segmental arm.

3. A feeding mechanism for sewing machines comprising a flat, narrow feed-bar provided with a V-shaped bottom edge; a feed-dog supported by said bar; a feed-lifting eccentric having a V-shaped groove in its periphery coöoperating with the bottom edge of said bar; mechanism for imparting the feed movements to said bar including a segmental arm, means for regulating the movement thereof, and means pivotally connecting the feed-bar to the upper end of said arm; and means for bodily adjusting said arm at an angle to the direction of feed movement of said feed-bar.

4. A feeding mechanism for sewing machines comprising a feed-bar; a dog carried thereby; means for giving said bar its vertical movements; means for giving said bar its feeding movements, the latter means including a vibratory arm pivotally connected to the feed-bar and having a pivotal support; and means for bodily adjusting said arm in the direction of its length, whereby to cause the feed-bar to tilt relatively to the machine work-plate, whereby the action of the feed-dog on the work may be changed.

In testimony whereof I have hereunto signed my name in the presence of two subscribing witnesses.

JOHN P. WEIS.
